UNITED STATES PATENT OFFICE.

RICHARD R. SCOGGAN, OF JEFFERSONVILLE, INDIANA, ASSIGNOR TO CHEATHAM ELECTRIC SWITCHING DEVICE COMPANY, OF LOUISVILLE, KENTUCKY.

ELECTRIC TRACK SWITCH.

Application filed December 23, 1924. Serial No. 757,670.

This invention relates to an electric track switch and more particularly to means under the control of the motor man whereby the track switch can be maintained in or 5 shifted to proper position electrically to enable the car to travel over the switch in the desired direction.

One of the objects of the invention is to provide simple and compact switch operating mechanism which can be placed readily 10 on any support in proximity to the track switch and the operation of which will depend upon the operation of the controller while the car is in a predetermined position 15 while approaching the switch.

With the foregoing and other objects in view which will appear as the description proceeds, the invention resides in the combination and arrangement of parts and in the 20 details of construction hereinafter described and claimed, it being understood that changes in the precise embodiment of the invention herein disclosed may be made within the scope of what is claimed without 25 departing from the spirit of the invention.

In the accompanying drawing, which shows the invention in diagram, the preferred arrangement has been illustrated.

Referring to the drawing by characters of 30 reference 1 designates the trolley and supported adjacent thereto are spaced pairs of contactors 2 and 3, and 4 and 5. These pairs of contactors may be disposed any desired distance apart and 2 and 4 are located at 35 a point where the trolley wheel W can engage them before the car reaches the track switch S. In the drawing the controller on the car has been indicated at C and the motor at M, the controller being electrically 40 connected to the wheel W in the usual manner and the motor being also grounded in the usual manner, as shown. These contactors may be constructed and mounted as shown in Patent #917,541, issued April 6th, 45 1909 to R. V. Cheatham, and the parts are preferably arranged in Patent #787,827, issued April 18th, 1905, to said Cheatham.

The contactor 4 is electrically connected to the trolley 1 by a suitable conductor 6 50 while the contactor 5 is electrically connected

by a conductor 7 to the coil of an electro-magnet 8, the other terminal of which is grounded as at 9 through a resistance 10.

The contactor 2 is electrically connected by a suitable conductor 11 to the coil of an 55 electro-magnet 12, and the other terminal of this coil is electrically connected, as by means of a suitable conductor 13, to the trolley 1. Contactor 3 is electrically connected as at 14, to a contact 15. This contact is normally engaged by one end of a lever 16, the other end of which is fulcrumed as shown at 17. This lever carries the armature 18 of the magnet 8 and connected to the lever adjacent this fulcrum is 60 a spring leaf 19 carrying a hammer head 20. The spring holds the head normally in contact with the lever but is so positioned relative to the electro-magnet 12 that when 65 said magnet is energized, the spring will be 70 attracted thereto away from the lever 16 and against the tension of the spring.

The lever 16 is electrically connected by a suitable conductor 20 to another lever 21 which is fulcrumed as at 22 and projects between spaced contacts 23 and 24. Contact 23 is electrically connected, as at 25, to one terminal of a solenoid 26 while contact 24 is electrically connected, as at 27, to one terminal of a solenoid 27. Both solenoids 80 are grounded as shown at 28 and the core 29, which is common to both solenoids, is operatively connected to the shifting members S' of the switch as shown. Pivotedly mounted on the fulcrum 22 of lever 21 is a 85 bell crank 30, one arm of which extends close to and is adapted to be attracted by the energized magnet 12 while the other arm of the bell crank projects under and bears upwardly against lever 21. A threaded 90 stem 31 projects from the bell crank and carries a weight 32 which serves to hold the bell crank normally in one position, as shown in the drawing, with lever 21 pressing against the contact 23. The resistance 95 in the switch solenoids 26 and 27 is arranged to draw from six to eight amperes.

It is to be understood that the entire apparatus illustrated except those parts mounted on the car, is to be located at a 100

point adjacent the track switch and, by reason of its compactness, can be easily mounted on a pole, post or other support without presenting an unsightly appearance.

5 When the motor man desires to take the straight track he shuts off the current to the motor M and coasts past the contactors 2 and 3. Consequently a current of from 10 six to eight amperes will start from the trolley wire and pass through the electro-magnet 12 from the conductor 13, through conductor 11 to contactor 2 and thence through wheel W and contactor 3 to the conductor 14 to the contact 15. From this contact 15 15 the current will flow through the lever 16 and conductor 20 to lever 21 and thence by way of contact 23 and conductor 25 to the magnet 26 and ground. This flow of current through the electro-magnet 12 will be sufficient to draw the spring or armature 19 20 away from normal position against the tension of spring. At the same time magnet 26 when energized will shift the switch tongue S' to proper position. As soon as the wheel 25 W leaves the contactors 2 and 3 the circuit will be broken and as the spring armature 19 is released, the head 20 will strike a hammer-like blow against the lever 16 with the result that said lever will be shifted 30 away from the contact 15 and remain in such position. As a result the mechanism is left inoperative until the trolley wheel reaches the next pair of contactors 4 and 5. At this time the wheel W engaging the contactors 4 and 5 will allow a current to flow 35 from the wire to the magnet 8 and through the resistance 10 to the ground. This energizing of the magnet results in the armature 18 being attracted so as to draw lever 16 40 back against the contact 15 and reestablish the operating condition or, as is termed by those skilled in the art, unlocks the switch.

Should the motor man desire to take the curve track at the switch, he does not shut off the power to the motor while passing the contacts 2 and 3. Instead the full current which should be twenty amperes or more is allowed to pass through the magnet 12 and as this current is sufficient to overcome 45 the weight 32 and attract the adjacent arm of the bell crank 30, lever 21 will be permitted to gravitate against contact 24 and thus close the circuit through the solenoid 27 to the ground. When the current is 55 broken as before stated, the spring armature 19, which has been attracted by the energized magnet 12, will be released and will strike against lever 16, and shift said lever away from the contact 15. Thus every operation 60 will be as before described.

It is to be understood that the armature 19 is operated by every car passing the switch because the spring tension is always overcome by the switch current of from six to 65 eight amperes passing through magnet 12.

It is to be understood that in this apparatus the circuit changing magnet performs two separate functions. First it acts to shift the lever 21 from one contact to the other and, second, it breaks the circuit or contact between the lever 16 and the contact 15. As far as is now known, this service has only been possible heretofore by the use of an additional magnet. It will be noted furthermore, that in the present apparatus, the cut-out is affected only after the switch current is cut off. No arcing of the cut-out is possible because it cannot function until the circuit is dead. Another feature of importance in this system is that if the motor man should pull the car under the contactor while the power is on and stop on the contactor, the lever 21 would remain down against the contact 24 although the motor current has been shut off. This is due to the fact that bell crank 30 would be attracted by the magnet 12 and while it takes twenty amperes to place it there, it will remain there under the magnetic pull of from six to eight amperes.

The levers 30 being mounted as described with reference to lever 21 can always come to proper position against the core of magnet 12 regardless of any variations in the movement of the lever 21. This apparatus effects a considerable saving in cost as well as in space required because of the reduction in the number of magnets necessary.

Although the current required to operate under different conditions have been stated as from six to eight amperes and twenty or more amperes, it is to be understood that any relatively low or high amperage can be employed.

I claim:

1. In an electric track switch having trolley wire contactors, track magnets, a control magnet adapted to be placed in series with the car motor and in circuit with the trolley wire contactor and one of said track magnets, armatures co-operating therewith, one of the armatures operating after the control magnet has been deenergized and the other armature co-operating with the control magnet to shift or change the circuit from one track magnet to another as the control magnet is connected in circuit with the car motor or not.
2. In an electric track switch having trolley wire contactors, track magnets, a control magnet operated by car motor current, an electric connection between a trolley contactor and the track magnets, a switch arm forming a part of said connection, a retractile armature co-operating with said switch arm and with said control magnet to break the circuit between the contactor and the track magnets after the control magnet is deenergized.
3. In an electric track switch having trol-

ley wire contactors, track magnets, an electric circuit connecting one of said trolley wire contactors and the track magnets, and a circuit changing switch and a circuit breaking switch forming a part of said circuit, two electric magnets located near the said switches, one magnet being connected to the trolley wire and to one of the contactors and operating in conjunction with both the circuit changing switch and the circuit breaking switch to change said circuit when the magnet is energized by a car motor current and to break said circuit after said magnet is demagnetized, the other magnet being connected to a second trolley wire contactor and to the ground and operating in conjunction with the circuit breaking switch to close the switch when the magnet is energized by current from the second trolley contactor.

4. A switch including opposed electromagnets for electrical connection with a track switch and separate contacts in communication with the respective magnets, said magnets having a relatively low amperage, a lever movably mounted between the contacts, a weighted armature for maintaining the lever normally against one of the contacts, means controlled by the movement of the trolley wheel to a predetermined position for setting up a current from a trolley wire through said lever to one of the switch magnets, said means including a lever carrying an armature and a contact normally engaged by the lever, a spring armature carried by the lever and normally in contact therewith, an electro-magnet for receiving a relatively high amperage when the motor current of the car is turned on, said high amperage magnet constituting means for attracting the weighted armature to release the first named lever for engagement with its second contact.

5. A switch including opposed switch magnets, a lever controlling the same, a trolley wire, spaced contactors, an electrical connection between the trolley wire and one of the contactors, said connection including an electro-magnet, an electrical connection between the other contactor and the lever, a weighted armature normally holding the lever to maintain a circuit to one of the switch magnets, and a trolley wheel constituting a means for establishing a circuit between the contactors, said electro-magnet adapted to be energized by a relatively high amperage when the current to the car motor is turned on, said amperage being sufficient to actuate the weighted armature and release the lever to complete a circuit to the other switch magnet.

6. A switch including separate switch magnets, a lever controlling the flow of current thereto, a trolley wire, separate con-

tactors adjacent thereto for engagement by a trolley wheel, means controlled by the movement of the trolley wheel into engagement with the contactors for setting up a current of low amperage through the lever and one of the track magnets, said means including a lever and a contact therefor, a magnet adapted to be energized by high or low amperage, a resilient armature carried by the last named lever for attraction by said magnet, said magnet when energized by a high amperage constituting means for shifting the lever of the track magnets to direct low amperage current into the other track magnet, said resilient armature constituting means for striking its lever when the current is broken through its magnet to knock the lever away from its contact and break the current to the track magnet.

7. A switch including a switch magnet, a trolley wire, contactors adjacent the wire, means controlled by the engagement of the wheel with the contactors for conducting a current to the switch magnet, said means including a contact, a lever normally engaging the same, and a resilient armature, and an electro-magnet included in circuit with the track magnet, for attracting the resilient armature, said magnet, when deenergized, releasing the resilient armature to strike the lever from its contact and break the circuit to the magnet.

8. A switch including a switch magnet, a trolley wire, contactors adjacent the wire, means controlled by the engagement of the wheel with the contactors for conducting a current to the switch magnet, said means including a contact, a lever normally engaging the same, and a resilient armature, an electro-magnet included in circuit with the track magnet, for attracting the resilient armature, said magnet, when deenergized, releasing the resilient armature to strike the lever from its contact and break the circuit to the magnet, additional contactors, a magnet and means controlled by the trolley wheel on the additional contactors for energizing the magnet to attract and reset the lever.

9. In an electric track switch having trolley wire contactors, track magnets, a control magnet adopted to be placed in series with the car motor and in circuit with one of the track magnets, having armatures co-operating therewith, one of the armatures co-operating with a control magnet and operable only when the said magnet is placed in series with the car motor, and the other armature equipped with means which is actuated each time the control magnet is energized to operate the said other armature after the said control magnet is de-energized.

10. In an electric track switch having trolley wire contactors, track magnets, a control magnet adopted to be placed in series with

the car motor, and in circuit with one of the track magnets, having armatures co-operating therewith, one of the armatures co-operating with the control magnet and operable only when the said magnet is placed in series with the car motor, and the other having a secondary spring member that is actuated

each time the control magnet is energized to operate the armature after the said magnet is de-energized.

In testimony that I claim the foregoing as my own, I have hereto affixed my signature.

10

RICHARD R. SCOGGAN.
